(57) **CLAIM**

The ornamental design for a ceiling fan light unit, as shown and described.

DESCRIPTION

FIG. 1 is an enlarged perspective view of a ceiling fan having a light unit constructed in accordance with the present invention, the ceiling fan providing an environment for the light unit;

FIG. 2 is an enlarged perspective view of the light unit in accordance with the present invention;

FIG. 3 is an enlarged bottom view of the light unit in accordance with the present invention; and,

FIG. 4 is an enlarged side view of the light unit in accordance with the present invention.

The broken line showing of a ceiling fan canopy, support pole, motor housing, blades and blade irons is included for the purpose of illustrating environmental structure and forms no part of the claimed design.
